BUCKLE

Filed Nov. 5, 1923

UNITED STATES PATENT OFFICE.

THEODORE H. MILLER, OF WATERBURY, CONNECTICUT, ASSIGNOR TO WATERBURY BUCKLE CO., OF WATERBURY, CONNECTICUT, A CORPORATION.

BUCKLE.

Application filed November 5, 1923. Serial No. 672,768.

To all whom it may concern:

Be it known that I, THEODORE H. MILLER, a citizen of the United States, residing at Waterbury, in the county of New Haven and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Fig. 1 a view in front elevation of a 15 rustless buckle constructed in accordance with my invention, shown as applied to a piece of webbing, which is partly broken away.

Fig. 2 an edge view thereof.

Fig. 3 a sectional view on the line 3—3 of Fig. 1.

Fig. 4 a view of the buckle-frame in front elevation on an enlarged scale.

Fig. 5 a plan view thereof, prior to the 25 closing of the web-gripping members of the frame, shown in their gripping positions by dotted lines.

My invention relates to an improvement in 30 rustless buckles of the type shown and described in United States Patent No. 847,811, granted March 19, 1907, on the application of Morris Peller, the object of my present invention being to produce a wire-frame buckle in which the wire of the frame is 35 bent to grip the fixed end of the webbing, whereby an economy of time, labor and webbing is effected, the sewing of the webbing to fasten it to the buckle being eliminated.

With these ends in view, my invention 40 consists in a wire-frame rustless buckle having certain details of construction as will be hereinafter described and pointed out in the claim.

As herein shown, I employ a buckle-frame 45 made by bending a single piece of wire to form a continuous upper bar 6 merging at its ends into downwardly-bent side bars 7, the lower ends of which are bent inwardly 50 until they nearly meet and then returned upon themselves to form complementary loops 8, which are set to be located in the vertical plane of the upper bar and which together form the lower bar of the buckle-

frame. The co-extensive lower reaches of 55 the said loops 8 are bent forwardly and inwardly in the horizontal plane of the lower reaches of the said loops to form gripping-arms 9, containing the respective ends to the wire. As thus shaped, the buckle-frame 60 has a relatively large webbing-opening 10. A sheet-metal buckle-lever, pivotally mounted upon the continuous upper bar 6 of the frame, comprises, as shown, a finger-piece 11 extending downward in front of the 65 said webbing-opening 10, a gripping-edge 12 and hinge-fingers 13, which loosely embrace the bar 6 and pivot the lever upon the frame.

In webbing my improved buckle, what is 70 to become the fixed end 14 of the webbing 15 is inserted between the lower reaches of the loops 8 of the frame and the gripping-arms 9 thereof, after which the latter are clamped down upon it to bite into and hold 75 it, as clearly shown in Fig. 3. The webbing is then passed from front to rear over the upper reaches of the loops 8, so as to form a friction-cushion 16, then downward to form the usual depending loop 17 and upward over the gripping-arms 9 and from 80 front to rear over the cushion 16 and under the gripping-edge 12 of the buckle-lever, whereby the webbing is permanently fastened to the buckle-frame without stitching 85 and with marked economy of time, labor, thread and webbing.

I claim:

A rustless buckle having a one-piece, wire 90 frame bent to form a continuous upper bar, side-bars, two inwardly-extending aligned loops forming the lower bar of the frame, and two inwardly-extending gripping-arms forming extensions of the lower reaches of 95 the said loops; of a buckle-lever pivotally mounted upon the upper bar of the frame in position to have its gripping-edge deflect the running portion of the webbing substantially over the upper reaches of the said 100 loops.

In testimony whereof, I have signed this specification in the presence of two subscribing witnesses.

THEODORE H. MILLER.

Witnesses:

MARTIN T. LYNN,
CHESTER LITTLE.
